UNITED STATES PATENT OFFICE.

WILLIAM M. BOENNING, OF PORT WASHINGTON, WISCONSIN.

ROCKING-CHAIR.

SPECIFICATION forming part of Letters Patent No. 585,422, dated June 29, 1897.

Application filed November 27, 1896. Serial No. 613,502. (No model.)

To all whom it may concern:

Be it known that I, WILLIAM M. BOENNING, a citizen of the United States, and a resident of Port Washington, in the county of Ozaukee 5 and State of Wisconsin, have invented certain new and useful Improvements in Rocking-Chairs; and I do hereby declare that the following is a full, clear, and exact description thereof.

10 My invention has for its object to provide a simple economical knockdown rocking-chair; and it consists in certain peculiarities of construction and combination of parts hereinafter set forth with reference to the accompanying drawings and subsequently claimed.

Figure 1 of the drawings represents a partly-sectional view of the major portion of a rocking-chair constructed according to my invention; and Fig. 2, a plan view illustrating the 20 base and rocker mechanism of the chair, parts of this rocker mechanism being broken.

Referring by letter to the drawings, A A represent a pair of parallel bars set on edge and joined by intermediate rounds b to constitute the base of my improved rocking-chair. Pivots connected to each side bar of the base, near the extremities of the same, are the lower ends of rods B C, that cross each 25 other and have their upper ends likewise connected to the side bars D of a seat-frame, the latter being supported by said rods at the desired elevation clear of said base.

The parallel pair of rods B are shown connected by a round c, and rounds d e are shown 35 connecting the other parallel pair of rods C, these latter rods being of greater length than those aforesaid for the purpose hereinafter specified. The rods C are shown as arranged to come inside of the ones B, and the round 40 c, connecting the outer rods, is in the downward path of the others to serve as a stop for the same.

As herein shown, a spiral spring E may have hook-end connection under tension with the 45 rounds c e, and resistance of the spring is therefore proportionate to the degree of tilt that may be imparted to the seat-frame in either direction. Consequently there is always a tendency of the movable parts toward 50 their normal position herein shown.

The rods C are made longer than the ones B in order to obtain normal rearward tilt of the chair-seat, and the base extends far enough in rear of said seat to compensate for any tendency of the chair to topple backward. 55

The rods B C are preferably of wood and their pivots of metal, those shown being engaged with corresponding sockets in the side bars of the base and seat-frame. As herein fully illustrated, the pivots may be extremities of shouldered arms extending from metal sleeves F in driving fit on ends of rods B C, and these sleeves are provided with apertures for stay-nails g, driven into said rods. 60

The pivotal connection of the crossed rods 65 with the base and seat-frame insures easy rocking action of the latter, the spring under tension operating to prevent sudden movement in either direction, thereby overcoming the sensitiveness that otherwise exists. 70

In view of what has been shown and described it is evident that the chair may be readily knocked down and the parts packed in comparatively small compass for storage and shipment. 75

Having now fully described my invention, what I claim as new, and desire to secure by Letters Patent, is—

1. A rocking-chair comprising a seat-frame, a base extended in rear of the seat-frame, and crossed rods in pairs pivotally connected to said seat-frame and base to support the former, the rods of the pair connecting the rear portion of the base with the aforesaid seat-frame being longer than those of the other 85 pair.

2. A rocking-chair comprising a seat-frame, a base extended in rear of the seat-frame, crossed rods in pairs pivotally connected to said seat-frame and base to support the former, the rods of the pair connecting the rear portion of the base with the aforesaid seat-frame being longer than those of the other 90 pair, and a round uniting the short rods arranged in the downward path of the long rods. 95

3. A rocking-chair comprising a seat-frame, a base extended in rear of the seat-frame, crossed rods in pairs pivotally connected to said seat-frame and base to support the former, the rods of the pair connecting the rear 100

portion of the base with the aforesaid seat-frame being longer than those of the other pair, rounds connecting each pair of rods, and a spiral spring having connection under tension with opposite rod-connecting rounds.

5 In testimony that I claim the foregoing I have hereunto set my hand, at Port Wash-

ington, in the county of Ozaukee and State of Wisconsin, in the presence of two witnesses.

WILLIAM M. BOENNING.
